[57] CLAIM

The ornamental design for an actuator overcap for a pressurized container, as shown and described.

DESCRIPTION

FIG. 1 is a right, top, front perspective view of an actuator overcap for a pressurized container embodying my new design;

FIG. 2 is a right, top, rear perspective view thereof;

FIG. 3 is a front elevational view thereof;

FIG. 4 is a right side elevational view thereof, the left side elevational view being a mirror image of the right side shown;

FIG. 5 is a rear elevational view thereof; and,

FIG. 6 is a top plan view thereof.

The bottom of the actuator overcap forms no part of the claimed design.
